UNITED STATES PATENT OFFICE.

ARTHUR GERALD GRAY, OF LONDON, ENGLAND.

DERRICK OR CRANE.

Application filed December 31, 1924, Serial No. 759,181, and in Great Britain January 1, 1924.

This invention relates to improvements in derricks or cranes, particularly to derricks or cranes for use on board ship, of the kind in which the goose-neck or the attachment of the topping lift to the mast is adapted to be moved transversely with respect to the mast.

The present invention has for its object generally to improve the construction of such derricks.

In the accompanying drawings illustrative of the invention,

Figs. 1 and 2 are fragmentary elevations at right angles to one another of a derrick embodying the invention;

Fig. 3 is an athwartship view of a barge equipped with a derrick of the invention;

Fig. 4 is a detail view of the table of the derrick in elevation;

Fig. 5 is a section on the line 5—5 of Fig. 4;

Figs. 6 and 7 are detail views of the arrangement of guy-rope rendering gear, and

Figs. 8 and 9 are, respectively, a fragmentary elevation and a diagrammatic plan view of the arrangement of derricks in a construction comprising four derricks associated with one mast.

As shown in Figs. 1 and 3, an eye at the foot of the derrick is fitted by a pin to a goose-neck 83, which is revoluble in a carriage mounted on track wheels. Stops (not shown) may be provided to engage with a stop on the gooseneck and limit the swing of the derrick to positions determined, or preferably the swing of the derrick may be arrested by stays (not shown) suitably placed on either side so that should the operator fail to release the brake rope an automatic check is provided.

Wheels 4 mounted on projecting bosses of the carriage 1, co-axial with the gooseneck, are fitted one above and one below the track wheels 5. The wheels 4 take the thrust of the derrick and are confined to straight-line motion by means of washer plates 54, 55, the plate 54 being fixed above the upper thrust wheel 4 and the plate 55 being fixed below the lower thrust wheel.

The carriage 1 is connected by means of a connecting rod 59 to a worm wheel 10 driven by a worm 11 and rotatably mounted on a pin 47 rigidly secured to an extension of the table.

Tracks 74 are provided on the table for the track and thrust wheels 4, 5, ensuring

straight-line motion of the carriage, gooseneck and derrick foot.

The worm is driven from a bevel wheel *x* keyed to the engine shaft of the winch 60 through a train including a bevel wheel *y*, a horizontal shaft *z*, bevel gears *c* and *d*, a vertical shaft 39 and bevel gears 63. The train may, however, be modified as circumstances demand, e. g., a worm may be keyed to the winch engine shaft driving a worm wheel, in lieu of bevels.

The bevel pinion *c*, which is loose on the horizontal shaft *z*, forms the non-sliding member of a clutch indicated at *e* (Fig. 1). The sliding member of the clutch *e* is caused to slide and engage by a fork *f* mounted on a spindle operable directly or indirectly by a foot-lever or hand lever (not shown). A spring disengages the clutch when pressure is taken off the lever. The clutch is, however, preferably of the coil spring type.

Brake sheaves 8, which may be situated under the base of the table, and are mounted for rotation on a fixed shaft 41; normally the rims of the sheaves 8 are contacted by a single brake block 7, which is urged towards the rims by helical springs 61 mounted on pins 48. The brake block is guided in a stationary yoke which is an integral part of the cage or casting *g* which carries the brake gear and the sheaves. The yoke carries the pins 48 and presents abutments for springs 61, which bear on the brake block urging it towards the rims of the sheaves.

A release pin 40, rigidly fixed in the brake block and penetrating the yoke, has threaded on its outer end a flanged nut 36, there being interposed between the flange of the nut and the yoke a thrust ball race 71. The nut is formed with a squared end 49, to which is fitted a lever 50 to which a rope or rod (not shown) may be attached for effecting angular displacement of said lever 50.

The thread of the nut is of very "quick" or coarse pitch, so that the pressure of the compressed helical springs 61 will normally cause the nut to revolve until the concave surface of the block presses against the sheave rims, thus securing contact under normal conditions.

Manually effected angular movement of the lever 50 by means of the rope or rod causes the pin 40 to advance in the flanged nut and thereby withdraw the brake block 7 from contact with the rims of the sheaves 8.

2
Each sheave 8 is provided with a small axle 8¹ to which is attached one end of a light rope 8², said rope being wound around the relative axle in the direction contrary to that of the winding of its respective guy rope. In the form shown in Fig. 4 the other end of each of the said light ropes (led over freely revolving guide pulleys 42 mounted on fixed spindles) is attached to 10 the eye of a bobweight 16, which latter is free to rise and fall inside of one of a pair of stanchions which, in addition to supporting the table and derrick, provide housings for the bobweight 16. The function of the 15 bobweights 16 is to rotate the sheaves 8 when the brake block 7 is released, taking in the slack guy and allowing the tight one to pay out, keeping both ropes just taut, thus permitting the arrest of the derrick 20 when the brake block is allowed to resume contact with the sheave rims.

When the derrick is swung around and the carriage is displaced (carrying the derrick foot with it) towards its mid-position, the topping lift, being of fixed length, causes the head of the derrick to lift and would produce undue tension in the guy ropes (which are wound around the brake sheaves, the latter being held fast by the rim brake) unless means were provided to allow the said guy-ropes to "render."

A preferred and simple form of rendering mechanism in accordance with the present invention, which necessitates no alteration to the derrick head, is illustrated in Figs. 6 and 7.

The mechanism, hereinafter described, is in duplicate, a complete set being fitted on each side of the vessel.

40 The guy-rope lead block *h* is attached by a pennant to the sheave 15, which is mounted to work freely on the fixed spindle 44. A helical spring 63 in tension tends to force the stop *i* on the sheave against a projection *j* provided on the casting 14. The lifting of the derrick head already described, transmitted to the guy-rope, overcomes the tension of the spring 63, causing a rotary movement of the sheave 15 around the spindle, in effect paying out the pennant and gathering it in when the derrick falls, and so restoring the original relative positions of the various members. This rendering action has also the effect of bringing up the derrick smoothly and of damping vibrations. As will be clear from Fig. 2, the movement of the pennant will be half the movement of the derrick head, owing to the interposition of the guy-rope lead block *h*.

60 In operation, suppose cargo is being discharged from the ship overside on the starboard side and the hook is being lowered into the hold.

65 While the hook is falling the operator depresses the foot-lever causing engagement

of the clutch *e* and displacement of the derrick foot to the port side. Then declutching is effected by removal of the foot from the lever. A fresh load is secured to the hook and raised clear of the rail.

70

The operator pulls the release rope or rod operating the lever 50, the brake block is withdrawn from contact with the sheave and the derrick swings to starboard as required; when the release rope is slackened the brake block functions and the derrick is arrested, the load is lowered and discharged. The empty hook is raised clear of the rail. While the hook is being raised the foot-lever is depressed actuating the clutch *e*, the derrick foot moved to starboard and the slewing gear declutched. The hook is now clear of the rail. When the release rope is pulled the derrick swings to its mid-position over the hatch centre. Then the release rope is slackened, the derrick is arrested, the hook lowered into the hold and the cycle of operations repeated.

75

It will be noted that the displacement of the carriage anticipates the swing of the derrick and is always effected with the derrick in an unloaded condition.

80

It will be noted that the displacement of the carriage anticipates the swing of the derrick and is always effected with the derrick in an unloaded condition.

85

To permit of operation when the ship has acquired a list, the topping lift attachment on the mast is made in the form of a nut 89 threaded on a screw-threaded shaft rotating in bearings fitted with bushes, this shaft being revolved, say, by means of an endless rope lying on the periphery of a halyard wheel 90 keyed to one end of the screw-threaded shaft.

90

The nut slides in a slot made in channels 91 which form part of the structure and take the pull of the topping lift transmitted to the nut, sliding contacts being formed between the nut and the surface of the channel nearest the mast.

95

In operation, when the ship is listed, the nut 89 is moved along the shaft in the required direction, until the eye of the same is perpendicularly over the centre of the gooseneck, when the carriage is in mid-position. No further movement is given to the nut while the same angle is maintained by the ship.

100

The gearing actuating the worm wheel controlling the carriage may be so arranged that the horizontal shaft driven from the winch and the worm wheel rotate at the same speed, and, with a suitable clutch adapted to engage in one position only, marks may be provided on the horizontal shaft which will afford to the operator an indication of the position of the carriage without the need for turning round to note the position.

105

In a general way, however, it is found preferable to fit a pointer to the carriage, which pointer travels on the front of the table. The movement of the pointer may be reflected in a mirror, suitably placed for the

110

115

120

125

130

operator or, if preferred, the movement of the pointer may be duplicated by means of the usual mechanism and placed in a spot convenient for observation.

5 1. I claim:—

1. A derrick comprising a mast and a jib, a support for one end of said jib disposed adjacent the base of the mast, a support for the other end of said jib adjacent the upper end of said mast and means for imparting a translatory movement to one of said supports with respect to said mast, braking means for said jib, such braking means including guy ropes and sheaves, said sheaves mounted on a single shaft, said guy ropes extending from both sides of said jib around said sheaves, and a braking device engaging said sheaves, said braking device comprising a brake block, spring means normally pressing said brake block on said sheaves and means including a nut formed with a thread of coarse screw-thread operable to release the brake but normally allowing the brake to be applied by said springs.
2. A derrick comprising a mast and a jib, a support for one end of said jib disposed adjacent the base of the mast, a support for the other end of said jib adjacent the upper end of the mast and means for imparting a translatory movement to one of said supports with respect to said mast, braking means for controlling said jib, said braking means including guy ropes and sheaves, said sheaves mounted on a single shaft, and means for loading said sheaves, said guy ropes extending from both sides of said jib around said sheaves and a braking device engaging said sheaves, said braking device comprising a brake block, spring means normally pressing said brake block against said sheaves, and means including a nut formed with a thread of coarse screw-thread operable to release the brake but normally allowing the brake to be applied by said springs.
3. A derrick comprising a mast and a jib, a support for one end of said jib disposed adjacent the base of the mast, a support for the other end of said jib adjacent the upper end of said mast, and means for imparting a translatory movement to one of said supports with respect to said mast, braking means for said jib, such braking means including guy ropes and sheaves, said

sheaves mounted on a single shaft, said guy ropes extending from both sides of said jib around said sheaves, a braking device engaging said sheaves, said braking device including a brake block, spring means normally pressing said brake block on said sheaves and means including a nut of coarse screw-thread operable to release the brake and on release to allow the brake to be applied by said springs, and means permitting said guy ropes to render, substantially as described.

4. A derrick comprising a mast and a jib, a support for one end of said jib disposed adjacent to the base of the mast, a support for the other end of said jib adjacent the upper end of said mast, and means for imparting a translatory movement to one of said supports with respect to said mast, braking means for controlling said jib, such braking means including guy ropes and sheaves, said sheaves mounted on a single shaft and formed with extensions, means tending to keep the ropes on said sheaves taut supported from said extensions, said guy ropes extending from both sides of said jib around said sheaves, and a braking device engaging said sheaves, said braking device including a brake block, spring means normally pressing said brake block on said sheaves and means including a nut of coarse screw-thread operable to release the brake but normally allowing the brake to be applied by said springs, substantially as described.

5. A derrick comprising a mast and a jib, a support for one end of said jib disposed adjacent the base of the mast, a support for the other end of said jib adjacent the upper end of said mast and means for imparting a translatory movement to one of said supports with respect to said mast, braking means for controlling said jib, said braking means including guy ropes and sheaves, said guy ropes extending from both sides of said jib around said sheaves and a brake engaging said sheaves, and means permitting said guy ropes to render, said means including spring-controlled sheaves and connections between said guy ropes and said spring-controlled sheaves, substantially as described.

In testimony whereof I have signed my name to this specification.

ARTHUR GERALD GRAY.
